UNITED STATES PATENT OFFICE.

DANIEL ROBERTS, OF BOOTLE, LIVERPOOL, ENGLAND.

SHIP'S BOAT CHOCK OR SUPPORT.

Application filed March 10, 1927, Serial No. 174,356, and in Great Britain May 21, 1926.

This invention has reference to movable chocks or supports for ships' boats, and it relates more particularly to that type which are movable in their beds or bases, and when 5 releasing the boat are free to move longitudinally in said beds or bases from their normal position.

According to the present invention, arms or devices are mounted on the chocks, say on 10 the outside faces, and adapted to be acted upon when the gear is actuated by plates or devices having a rocking or to and fro motion which so acts on the chocks as to move them away from one another and the boat; 15 and in one arrangement the devices on the chocks are in the form of arms which may be movable and mounted on hinges, so that they can be moved on these hinges to an inclined position, say for instance about 45° 20 and folded against the chock surfaces, the hinge mountings have a stop part thereon, which serves to limit their movement. The arms or devices on the chocks on which the plates or devices act when the gear is oper- 25 ated, are so constructed and adapted, that after the chocks have been moved apart on their slide bases by the action of the gear, they press the chocks outwards from their normal vertical planes, and cause them to 30 topple over, and out of their bases onto the ship's deck, or out of the way of the boat in its launching movements.

In one arrangement the plates or devices which operate on and move the chocks con- 35 stitute also chock locking and releasing de- vices, and they are mounted on rods or bars, supported in bearings and lying parallel with the chock surfaces; and conveniently fixed to the chock bases.

40 The actual supporting surfaces of the chocks will be inclined and shaped to the con- tour of the boat fore and aft, and thus by the arrangement above described, and the movement of the chocks from the normal plane, they move towards a narrower por- 45 tion of the boat surface, which enables the free fall of the chocks to take place with certainty.

The boat normally rests on rollers under 50 the keel, which is provided with projecting parts, which rest on the rollers; and when the launching operation is taking place, and the chocks cleared out of the way by the plates of the gear above described, by mov- 55 ing the boat—which will be slung taut on its tackles—a slight distance longitudinally, the

projecting parts will run off the rollers, and so the boat will be fully suspended by the tackles, and it can be easily swung outboard.

In order that the plates or devices which 60 actuate the chocks and press them apart in the commencement of the launching and freeing operation, may be moved outwards in opposite directions, the rod or shaft on which one set is mounted or supported on the 65 outside of the chock supports or bases is not directly actuated by the operating gear at the other end of the gear, but this rod or shaft is provided with a toothed wheel mounted in a suitable bearing, and meshes with an- 70 other toothed wheel in said bearing; and on the spindle of this wheel, the operating or moving lever is mounted, such lever being connected with the operating lever at the opposite end by a suitable connecting rod.

If in the action of the freeing or actuating gear the chocks are not moved quite clear of the course of the boat when moving it out- 75 board, or they are loose and free, it can easily knock them aside.

A locking device, consisting say of a cleat, is fixed on one of the axle bars, and is passed over an eye say on the base or support of the chocks, through which, when the cleat is 80 passed over the eye, a locking pin or key can be introduced, and so the whole gear is locked.

The invention is illustrated by and will be further described with reference to the accom- 85 panying drawings, in which Figure 1 is a side elevation, and Figure 2 is a plan showing the gear; and Figure 3 is an end view, and Figure 4 a plan in detail of the right hand chock, shown on a larger scale.

Referring to the drawings, 1 are the chocks proper having projecting ribs on their bot- 90 toms, and 2 the bases which are correspondingly grooved on their upper surfaces, on which the chocks rest and are adapted to slide.

3 are the actuating and locking plates or devices mounted on the rods 4, supported in bearings 5 at the operating ends of the rods, and intermediate and end bearings 6 fixed to the slide bases 2.

The operating of the rods 4 is effected through a hand lever 7, which on the left hand chock is a continuation of the lever portion 8 of the rod 4. At the right hand end, the lever 8 is mounted on a spindle 4* 110 mounted in the bearings 5 at this end; the two levers being connected together by the

connecting rod 9; and at this end the rod 4 is operated from the lever 8 through toothed wheels 12, the bearing 5 having two flanges or cheeks on a base, and the two wheels 12 mounted between them, and the lever 8 on the spindle 4^x also lies within these cheeks. By this arrangement, when the chocks are pressed by the devices 3, tending to cause them to topple from their bases 2, both sets 10 of them are pressed outwards towards the end of the boat, and thus they move towards the narrower part of it, and therefore their falling is not impeded or interfered with in any way and therefore a free and unstructured way for the launching of the boat 15 outboard.

Normally, when in the chocks, the boat rests on rollers 10 carried in bracket bearing 11, mounted on the slide bases 2, and a point 20 intermediate same; the boat keel being provided at the points where the rollers come with projecting portions 10^x.

The devices on which the plates 3 act to press the chocks apart, and cause them to 25 topple off their bases 2, are marked 13; and in the case shown, the plates 3 also serve as locking devices to the chocks when in their supporting position; and in locking the chocks, they are caused to enter slots in the 30 outside faces of the chocks. The devices 13 shown, are in the form of arms; and they are hinged at 15 in brackets 16, the outer ends of which extend beyond the hinges 15 and forming a stop, so that when the gear is to 35 be operated, and the arms 13 are in their outer position, they will be held at the required angle, such as that shown, so that by pulling on the actuating lever 7, the backs of the plates 3 will act on the two inclined arms, and cause the chocks to slide on their grooved 40 bases 2 away from one another, so as to be clear of the boat. By the further movement of the hand actuating lever 7, the plates 3 will act on the inwardly turned ends 13^x of 45 the arms 13, and this further pressure acting on these parts, will have the effect of tending to push the chocks 1—which are now free of the boat—to fall bodily outwards from their normal plane, and off their bases 2, so 50 that they will then become quite clear of the boat in its launching movements; and as stated, this movement of both sets of chocks is outward and towards the narrower parts or ends of the boat. But even if by some 55 chance the chocks should not be toppled over or moved clear away by the action of the devices 3, they are quite free, and by the movement of the boat longitudinally in its launching actions, they would be pushed over, and 60 tumble down on to the deck.

When the chocks fall over towards the deck, the hinged arms or members 13 will come in contact with it, and through their 65 hinges they can fold up against the chocks when they strike the deck, and thus the

chocks can fall and lie practically flat down on the deck, and thus be entirely removed from interference with the boat's action.

As above stated, the projecting portions 10^x of the keel of the boat rest on the rollers 10, and in the launching operation of the boat when the chocks are clear out of the way as described, the boat 10 (which will be slung on its tackles) will be moved a short distance longitudinally, whereupon the parts 10^x will be run off the rollers 10, and so the boat will be fully suspended by the tackles, and it can be easily swung outboard through and outside its pivoted davits in the usual way.

To replace the boat in the chocks, after being swung by the davits over the chocks, which will have been moved to their normal housing position and locked, and the keel projections 10^x are over the rollers 10, the boat is lowered until the projections rest on 85 the rollers.

A locking device consisting of a hinged cleat 17 is fixed on the rods 4, and works over an eye 18 fixed in the slide bases 2, so that normally this cleat will lie over the eye 18; and it is secured in position by a pin passed through the eye, as shown. When the boat 90 is to be launched the pin is removed, thus freeing the gear.

What is claimed is:—

1. In the ship's boat chock gear, chocks at each end of the boat adapted to be moved laterally away from each other, shafts parallel with the surfaces of the chocks, and adapted to be turned axially, a hand operating mechanism for turning the shafts, inclined devices on the faces of the chocks, arm devices on the shafts adapted to act on the inclined devices and move the chocks apart, and parts on the inclined devices adapted also to be acted upon by the arm devices and press the chocks out of the plane in which they normally stand, and cause them to topple over.

2. In the ship's boat chock gear, chocks at each end of the boat adapted to be moved laterally away from each other, shafts parallel with the surfaces of the chocks, and adapted to be turned axially, a hand operating mechanism for turning the shafts, hinged inclined devices on the faces of the chocks, arm devices on the shafts adapted to act on the inclined devices and move the chocks apart, and parts on the inclined devices adapted also to be acted upon by the arm devices and press the chocks out of the plane in which they normally stand, and cause them to topple over.

3. In the ship's boat chock gear, chocks at the opposite ends, operating axially rotative shafts on the outside surfaces of the chocks, inclined devices on the outside surfaces of the 125 chocks, arm devices on the shafts for acting on the inclined devices for moving the chocks at the same end of the boat laterally apart, and parts on the inclined devices adapted when acted on the arm devices to press the 130

- chocks at the opposite end of the gear in opposite directions and towards the narrower or smaller ends of the boat, and to topple them over outwards from one another.
- 5 4. In the ship's boat chock gear, chocks at the opposite ends, operating axially rotative shafts on the outside surfaces of the chocks, inclined devices on the outside surfaces of the chocks, arm devices on the shafts for act-
10 ing on the inclined devices for moving the chocks at the same end of the boat laterally apart, and parts on the inclined devices adapted when acted on by the arm devices to press the chocks at the opposite end of the gear in
15 opposite directions and towards the narrower or smaller ends of the boat, and to topple them over outwards from one another; the shaft at one end of the gear having toothed wheel on it, and a toothed wheel on
20 the separate shaft or spindle; the latter shaft or spindle being connected with the shaft at the other end of the gear by connecting by a rod, so that the two sets of devices connected with the two sets of chocks act together.
- 25 5. In a ship's boat chock gear, chocks at the respective ends of the boat mounted to be moved laterally relative to each other, means on the chocks to insure a relative movement of the chocks in operation, and a hand-oper-

ated mechanism including devices to act on 30 said means to thereby compel a relative movement of the chocks.

6. In a ship's boat chock gear, chocks at the respective ends of the boat the chocks at each end being movable laterally relative to 35 each other, shafts arranged parallel with the surface of the chocks, hand-operating devices for turning the shafts, means on the chocks for causing them to move relatively when acted upon, and arm devices on the shafts to 40 act on said means and move the chocks relatively to permit them to topple over.

7. In a ship's boat chock gear, chocks at each end of the boat adapted to be moved away by each other from the under surface 45 of the boat, means on the chocks adapted when acted upon to move the chocks at the same end of the boat laterally away from each other, shafts parallel with the surface of the chocks adapted to be turned axially, hand 50 operating mechanism for turning said shafts, arm devices on the shafts adapted to act on the means on the chocks and move them out of the plane in which they normally stand and cause them to topple over. 55

In testimony whereof I have signed my name to this specification.
